DECONCENTRATOR

Wilbur H. Armacost, New York, N. Y., assignor to
The Superheater Company, New York, N. Y.

Application December 15, 1932, Serial No. 647,331

6 Claims. (Cl. 122—459)

The present invention relates to devices of the general type disclosed in United States application for patent Ser. No. 600,864, filed by J. A. Powell on March 24, 1932, having for their object the purification of steam coming from boilers. The principal impurities in such steam are not in the form of solids carried along directly by the steam but are held in solution or in suspension in the moisture entrained by the steam. The general principle on which such a device operates is to let the steam from the boiler bubble through water, in a separate drum, the concentration of impurities in which water is much less than the concentration in the boiler. In practice feed water on its way from the hot-well to the boiler is used. The steam in passing through this water will ordinarily carry moisture with it which may approximate in amount that which was taken from the boiler as the steam flowed from the boiler. The moisture which the steam may carry along as it is liberated from the purer water in the drum is thus substituted for the relatively highly concentrated moisture which it brought with it from the boiler. The term "deconcentrator" has been accepted as the name for this apparatus and will be used herein. Its significance of course is that the impurities in the steam are reduced in amount by the arrangement.

The arrangement shown in said application presupposes that the deconcentrator drum be located at a level higher than the water level of the boiler. The amount which it is raised above such level depends upon conditions under which the device is to function.

The object of the present invention is to make available a deconcentrator of this type for some conditions under which the arrangement shown in the application cannot be used.

The relatively pure water in the deconcentrator drum is preferably feed water for the boiler. The steam is discharged into the body of the water by suitable nozzles. A part of the steam will be condensed and its latent heat will raise the temperature of the incoming feed water to the vaporizing point. A further amount will be condensed to make up for radiation heat losses. The remainder of the steam will either bubble directly through the water, the identical steam leaving the surface of the water in the deconcentrator drum or possibly some of it may condense and evaporate water to replace it. Which of these two happens is immaterial. In any event, every particle of the steam comes into intimate contact with water in the deconcentrator drum and is thoroughly washed. This steam is next led either

directly or via a superheater to the point of consumption.

The water in the deconcentrator drum is, as stated above, preferably feed water on its way to the boiler and is of the ordinary chemical purity of such feed water. It may, for example, be taken from a hot well with the addition of the necessary makeup water. It is fed into the deconcentrator drum at a rate corresponding to that at which steam is led from the boiler drum into the deconcentrator drum except for the variation occasioned by the additional heat required to heat up the feed water and to make up for radiation losses.

To carry the feed water from the deconcentrator drum to the boiler there is a connection from the water space of the former to the latter preferably with a provision to prevent the water level in the deconcentrator drum from falling below a predetermined level.

In such an arrangement it has heretofore been essential, as mentioned above, that the deconcentrator drum be placed at an elevation above the boiler drum, the distance depending upon the difference in pressure between the two drums. This pressure difference is occasioned by the resistance of the steam flow from the boiler to the steam space of the deconcentrator drum, such resistance being partly due to friction losses in the pipe and discharge nozzles, and partly to the head of water against which the steam is discharged. The required height will for an average case be a matter of a few feet.

If such an appliance is to be used in connection with a locomotive boiler or in connection with some other boiler where the necessary head room is not available, a serious difficulty at once arises, which my invention is intended to overcome. This difficulty relates to the rate at which water is fed to the deconcentrator drum and the rate at which it is carried from the deconcentrator drum to the boiler.

There are several factors which affect the water level in the deconcentrator drum. There is first the rate at which water is forced into it by the feed water pump. Next there is the rate at which water is removed from the drum and led to the boiler. Then there is the fact that a certain fraction of the steam from the boiler on its arrival in the deconcentrator drum is condensed in heating the feed water to boiler temperature without evaporating any of the water. This condensate is added to the water in the deconcentrator drum. Further the amount of moisture introduced by the steam may not, and probably

will not, balance exactly the amount carried away by the steam leaving the deconcentrator drum. Further, heat radiation losses from the deconcentrator drum will be made up by steam which 5 condenses and for which no equivalent amount will leave the deconcentrator.

All of these factors can readily be disregarded in the arrangements such as shown in the said application as the level in the deconcentrator 10 drum will automatically remain constant from the nature of the arrangement; but to make possible installations where the deconcentrator drum cannot be placed the required distance above the boiler water level, provision must be made to supply water to, and to remove water from the drum at the proper rates. My invention provides a system presenting a solution to this difficulty.

In the drawing the single figure represents diagrammatically an installation of the sort referred 20 to and embodying my invention. The boiler drum is shown at 1 and the deconcentrator drum at 2, the latter being below the average water level 3 of the boiler. The mixture of steam and water from the boiler tubes 4 is discharged into the 25 boiler drum 1, where the steam is separated out, and from which, together with its entrained moisture, it flows to the deconcentrator drum 2 by means of the pipe 5. It is discharged under the water level of the deconcentrator drum by the 30 nozzle 6. The steam generated in the water of the deconcentrator drum or bubbling through such water and collecting in the steam space of the drum 2 leaves said drum by means of the pipe 7, being carried, preferably by way of a superheater, 35 to the point of use. Water is fed into the deconcentrator drum by any preferred pumping means through the pipe 8. This pipe 8 discharges the water into the trough 9 in the drum. From this trough the water flows through a series of weirs 40 formed in its long free edge into the drum space proper, being forced by the baffle 10 to flow first downward toward the bottom of the drum. This water forced in through pipe 8 is, as in the original Powell application, the feed water for the boiler 45 and is of relatively very low concentration. It leaves the drum 2 to flow to the boiler through pipe 11, falling first through a series of weirs in the upper edge of plate 12 into the space 13. This prevents the water level in the deconcentrator 50 drum from falling below the level of these weirs.

As the drum 2 is at a point such that the water cannot flow from it by gravity to drum 1, means must be employed to force it. For this purpose a steam turbine and pump are employed. The steam turbine is shown at 14. It is operated by the steam flowing through pipe 5 on its way from the drum 1 to the drum 2. The pump is shown at 15 and it delivers water from the pipe 11 to the pipe 16 and so to the 60 boiler.

The pressure difference between the deconcentrator drum 2 and the boiler drum 1 is only a matter of a few pounds and the turbine 14 and pump 15 are designed so they are able to pump 65 water at a rate in excess by weight of the maximum rate at which the steam passes through the turbine 14. The rate at which the water is actually pumped is regulated by the valve 17, whose position varies in response to the changes 70 in the water level 3. This is effected by means of a float control 18 which sets the valve 17 in response to such level changes, opening it more if the level drops and closing it more if the

level rises. When the valve 17 is throttled down so that the water passes at a rate less by weight than the steam is passing through the turbine 14, the pump 15 will, due to the nature of such pumps, still perform satisfactorily.

The water level in the deconcentrator drum is kept up to the required point and not allowed to exceed it by means of the float controlled valve 19. The float for this is shown at 20 and regulates the valve 19 so that the level in the deconcentrator is kept up to but does not exceed the desired point.

In this manner all discrepancy in the rate at which water enters drum 2 and the rate at which it leaves that drum, due to the factors pointed out above is taken care of and a system is provided functioning as smoothly as the one in which the deconcentrator drum is arranged at the elevation heretofore required.

What I claim is:

1. In apparatus of the class described the combination of a boiler, a drum, connections whereby feed water on its way to the boiler passes through said drum, means to cause steam from the boiler on its way to the point of use to pass 100 through the water in the drum, a pump to force the water from the drum into the boiler, and an engine driven by the steam on its way to the drum actuating said pump.

2. Apparatus in accordance with claim 1, the 105 drum being so located relatively to the boiler that under normal operating conditions water will not flow by gravity into the boiler from the drum.

3. Apparatus in accordance with claim 1, the 110 drum being so located relatively to the boiler that under normal operating conditions water will not flow by gravity into the boiler from the drum, the apparatus further comprising a valve between the pump and the boiler to regulate the 115 rate at which water is fed from the drum to the boiler.

4. In apparatus of the class described, the combination of a boiler, a drum, means to force water into the drum, a turbine-driven pump, 120 means to cause steam from the boiler on its way to the point of use to drive the turbine and to pass through the water in the drum, means to deliver water from the drum to the pump and from the pump to the boiler, the design of the 125 turbine and pump being such that the pump is always capable of delivering more water by weight from the drum to the boiler than there is steam flowing through the turbine, and a valve in the means to deliver water from the pump 130 to the boiler operative responsively to the water level in the boiler limiting the amount of water delivered.

5. Apparatus in accordance with claim 4, the means to deliver water from the drum to the 135 pump being such that the water in the drum cannot be lowered by the pump below a predetermined point.

6. Apparatus in accordance with claim 4, the means to deliver water from the drum to the 140 pump being such that the water in the drum cannot be lowered by the pump below a predetermined point, the apparatus further comprising means responsive to the level of the water in the drum to control the rate of water supply to 145 the drum.
